LEATHER PURSE MADE FROM ONE-PIECE
BLANK WITH STORAGE SECTION IN TAN-
DEM WITH WINDOWED DISPLAY SECTION

Leopold G. Stanley, Maplewood, N. J.

Application August 12, 1944, Serial No. 549,173

2 Claims. (Cl. 150—37)

1

This invention is a novel leather purse, of the type wherein the case has a storage section for coins or like articles, and a display section, in the general nature of a tray, to which the articles may readily be slid at will from the storage section, for display and access, and similarly returned to the storage section; the case in its preferred form as illustrated being composed of or manufactured from a single unitary piece or blank of leather or similar limp sheet material. A good example of such type of pocket case or coin purse is that shown in Figs. 1 to 6 of my copending application Serial No. 453,500, filed August 4, 1942, Patent Number 2,368,687, issued February 6, 1945.

The general object of the present invention is to provide a coin purse or similar case which is not only of great convenience in operation and compact and durable in use, but simple and inexpensive in manufacture, with savings in material and labor and permitting marketing at a low price. A further object is to provide a coin purse which in a simple and easy manner may be manufactured from a single sheet or blank of leather or the like, initially stamped or cut out to a given contour, and then having its several sections overfolded upon each other, with a minimum of edge stitching to secure permanently the layers into the desired finished form, having its display or window section at one end of the complete case, which may be closed by folding about a central fold line, and at the other end a storage section, which communicates with the display section when the case is open but which becomes locked against exit of coins when the case is folded and closed; and with preferably an extension at one end which, in the complete purse, forms an interior supplemental pocket, as for holding folded bills, cards or tickets, facing the general or main central hinge of the case. Other and further objects and advantages will be explained in the hereinafter following description of an illustrative embodiment of the invention or will be understood by those conversant with the subject.

To the attainment of such objects and advantages the present invention consists in the novel leather purse, and the novel features of combination, arrangement and structure herein illustrated and described.

In the accompanying drawings,

Fig. 1 shows at full length a face view of a leather piece or blank after being cut out in the preferred manner for the manufacturing of the case of this invention.

2

Fig. 2 shows the same blank after the overfolding upon the outer layer of the inner layer and the extension layer, all shown in tandem in Fig. 1.

Fig. 3 is a similar view showing the completing steps of stitching longitudinally along the side edges, thus uniting the three layers, and stitching a tab piece provided at the display section in the cutting of the original blank.

Fig. 4 is a side edge view of the purse shown in Fig. 3.

Fig. 5 shows the purse of Figs. 3 and 4 after it has been closed and fastened by the tab means.

The disclosed purse has certain general features in common with said prior patent, being a purse for coins and the like comprising peripherally interconnected outer and inner layers 10 and 11 of sheet material and having a storage section 18 and a display or tray section 19, the two intercommunicating longitudinally between the outer and inner layers when the purse is open, but the storage section being closed and sealed when the purse is closed by the folding together of the two sections about their central lateral hinge line, and the display section having an access window slightly smaller both longitudinally and laterally than the section thereby providing a loose marginal strip 25 instanding from the periphery, thus to constitute an edge 30 rim around the end and both sides of the display section, and of narrow width.

The present improvement is characterized in one aspect in that the purse is constructed of a one-piece blank having the outer layer unitary in tandem with the display end of the inner layer at one end and at the other end with a short extension layer 12; the inner layer 11 being overfolded about the fold line 14 upon the outer layer 10 and the extension or overlapping layer 12 being overfolded upon the inner layer about the fold line 15, and the three layers being stitched together by the longitudinal stitch lines 17 along their side edges. This completes the purse as far as described, and the exterior layer 40 forms with the inner layer a flat pocket 20 at the storage end of the purse opening toward the central hinge line 16.

The display opening or window 22 in the inner layer 11 is preferably formed in the manner shown, namely, by means of a cross slit 23, slightly removed from the general hinge line 16 and a pair of apertures 24 at which the material is cut out of the blank. This provides a large tab 26 which, in Figs. 1 and 2, appears to block 55 the access window of the purse but which, in its

final form, constitutes a manipulating and locking tab, bent longitudinally outwardly, to extend beyond the inner layer 11, and there carrying a snap fastener or socket member 27 which, in the final closing, may cooperate with a fastener stud member 28 at the outer side of the outer layer 10. The tab 26, where it is bent longitudinally outward, is preferably flattened or fastened upon the end marginal rim 25, for example by a line of stitching 29 applied before the lines of side stitching 17, 17 are applied.

The tab 26 not merely serves to lock closed the purse as in Fig. 5, but is useful when the purse is in open position as in Fig. 3 for manipulating the rim 25 surrounding the display window. When the purse is open the coins within the storage section may be slid through into the display section by tilting the purse, and at this time the tab 26 can readily be pulled upon, thus swinging upwardly the marginal rim, so that the coins are safely received as in a tray.

Aside from the stitching 29 of the end tab 26 when used, the only stitching necessary consists of the two stitch lines 17 along the two sides of the purse, each stitch line connecting the inner to the outer layer and the overlapping extension layer to both of these. The ends need no stitching, since they are naturally closed by the smoothly rounded fold lines 14 and 15, providing a very slightly finished article.

What is claimed is:

1. A purse for coins and the like comprising peripherally interconnected outer and inner layers of sheet material, and having a storage section and a display or tray section, the two sections intercommunicating longitudinally between said layers when the purse is open but the storage section being closed when the purse is closed by the folding together of the two sections about their central lateral hinge line, and the display section having the inner layer cut-away to form an access window slightly smaller both longitudinally and laterally than the display section, thereby providing a flexible marginal strip instanding from the periphery, to constitute a narrow edge rim around the end and both sides of the section; and characterized in that the purse is constructed of a one-piece blank having the outer layer unitary in tandem with the display end of the inner layer at the display end, and at the storage end with a short extension layer; the inner layer being overfolded upon the outer layer at the display end and the extension layer upon the inner layer at the storage end, thus producing full width folds and squared ends, and the three layers being stitched together longitudinally from end to end along their side edges; the overfolded extension layer forming with the inner layer a short overlying flat pocket at the storage end of the purse opening toward the central hinge; and characterized further in that a substantial integral portion of the window cut-away material is left unsevered from the mar-

ginal end strip and forms a tab unitary therewith which is bent and secured to the end strip to project outwardly endwise well beyond the display section end that is remote from the hinge line, and is provided with fastening means to fasten its end to cooperating fastening means on the outer side of the outer layer, thereby to secure the closed purse in closed position; and said tab being also adapted to be pulled to manipulate the marginal end rim to stand up as a barrier to the spilling of coins being slid from the storage to the display section.

2. A purse for coins and the like comprising oblong outer and inner layers of leather material with squared ends, said layers being integrally united endwise as a single piece of leather and flatly interstitched along their side edges, and consisting of storage and tray sections intercommunicating longitudinally between said layers when the purse is open but the storage section being closed when the purse is closed by the folding together of the two sections about their central lateral hinge line, and the tray section in the inner layer being cut away to provide a space forming an access window slightly smaller both longitudinally and laterally than the section, thereby providing a narrow flexible marginal strip instanding from the periphery, to constitute an edge rim surrounding the window around the end and both sides of the section; wherein a substantial portion of the cutaway material of the window space remains unsevered from the end marginal rim and forms a tab which is adapted to be bent outwardly endwise to project well beyond the tray section end, and said tab being adapted to be pulled to cause the tray section end rim to stand up as a barrier against endwise spilling of coins sliding from the storage section on to the tray section; and wherein the tab is bent flatly out endwise against the end rim and near its bend is affixed against the end rim to maintain its endwise projecting disposition.
